(57) **CLAIM**

The ornamental design for an umbrella canopy with misting system, as shown and described.

DESCRIPTION

FIG. 1 is a front perspective view of an umbrella canopy with misting system, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a sectional view taken along lines 8-8 of FIG. 6. The broken lines showing of the water mist sprays in FIG. 1 is for illustrative purposes only and form no part of the claimed design.

1 Claim, 6 Drawing Sheets
